UNITED STATES PATENT OFFICE.

EDGAR W. SMITH, OF CARBON, ALBERTA, CANADA, ASSIGNOR OF ONE-HALF TO
ALEXANDER J. MCLEOD, OF CARBON, CANADA.

HARROW.

1,108,261.

Specification of Letters Patent. Patented Aug. 25, 1914.

Application filed January 19, 1914. Serial No. 813,008.

To all whom it may concern:

Be it known that I, EDGAR W. SMITH, a citizen of the Dominion of Canada, residing at Carbon, in the Province of Alberta and Dominion of Canada, have invented certain new and useful Improvements in Harrows, of which the following is a specification, reference being had to the accompanying drawings.

10 This invention relates to new and useful improvements in harrows and more particularly to that type known as roller harrows wherein a plurality of rollers are provided having teeth adapted to engage the soil to thoroughly pulverize the same as the harrow is drawn thereover.

Another object of my invention is the provision of a harrow of this character wherein the rollers are so arranged that when the 20 frame of the harrow is drawn in a straight line, the rollers will diagonally engage the soil and thoroughly pulverize the same, this form of harrow engaging more of the earth than the well known harrows wherein the 25 rollers are arranged in a longitudinal position.

Another object of the invention is the provision of a harrow of this character which will possess advantages in points of efficiency and durability, is inexpensive of manufacture and at the same time is simple in construction and operation.

With the above and other objects in view, this invention consists in the novel features 35 of construction and the combination and arrangement of parts to be hereinafter more fully described, pointed out in the claim and shown in the accompanying drawings, in which—

40 Figure 1 is a top plan view of a harrow constructed in accordance with my invention; Fig. 2 is a rear elevation; Fig. 3 is a front elevation.

Referring more particularly to the drawings, 1 and 2 indicate two substantially rectangular frames which are arranged in divergent relation and connected at their outer ends by having the inner corners thereof flattened and riveted together, as shown at 3, 50 the outer corners of the frames being suitably connected by means of a transverse bar 4. These rectangular frames 1 and 2 are preferably constructed of metal, the outer side portion thereof having its inner end extending transversely across the rear portion

of the main frame of the harrow, the ends forming the outer side portions of each of the frames being connected together at the rear end of the harrow by means of a U-shaped member 5, the ends of said member 60 being rigidly secured to the ends of the bars. A colter or guide wheel is mounted within the U shaped member 5 and is adapted to hold the harrow from any side draft.

Arranged between the inner sides of the 65 frames 1 and 2 and connected thereto and to the transverse end portions 7 is a cross piece 8 in which is formed a bearing 9 adapted to receive the spindle 10 of the roller 11, the other end of said roller being mounted with in a second U-shaped member 12, the ends of which are secured to the inner side portions of the frames 1 and 2. It will be noted from the accompanying drawings that the rollers 11 are arranged upon opposite sides of the 75 center of the harrow and are disposed at an angle in divergent relation with respect to the center.

Arranged within the frames 1 and 2 are the rollers 13 which are arranged in sets in 80 each of the frames, having their ends rotatably mounted within the end portions of the frame. These rollers 13 are disposed at divergent angles with respect to the center of the harrow and in parallel relation with 85 the rollers 11. The rollers 11 and 13 are provided with outwardly projecting teeth 14 which are arranged in alternate staggered relation upon the peripheries of the rollers and are adapted to engage the soil to 90 loosen the same as the frame is dragged thereover.

Secured to the forward ends of the frames 1 and 2 and arranged upon the outer sides thereof are the loops 15 to which is secured 95 the doubletree 16. From the above it will be readily apparent that I have provided a simple and durable harrow which is extremely simple in construction, the frame portion thereof being preferably constructed 100 of metal while the rollers may, if desired, be formed of wood or any other suitable material. It will be noted that by the peculiar arrangement of the rollers that the soil will be more thoroughly pulverized, than by the well known form of harrow in use at the present time. It will also be apparent that my device is extremely simple in construction and can be manufactured at a comparatively low cost.

While I have shown and described the preferred form of my invention, it will be obvious that various changes in the details of construction and in the proportions may 5 be resorted to for successfully carrying my invention into practice without sacrificing any of the novel features or departing from the scope of the appended claim.

What I claim is:—

- 10 A device of the class described including divergent frames having their inner corners rigidly connected, the rear portions of said frames having portions extending part-way across the rear of the harrow, a U-shaped member connecting the extended portions at 15 the central portion of the harrow, a second

U-shaped member arranged between the frames adjacent the forward corners thereof, angular pieces between each frame and extended portion, rollers disposed between 20 the second U-shaped member and the angular pieces, and a second set of rollers rotatably mounted within each of said frames, and teeth carried by said rollers, as and for the purpose set forth. 25

In testimony whereof I hereunto affix my signature in the presence of two witnesses.

EDGAR W. SMITH.
